BICYCLE SEAT COVER

Albert J. Fritz, Wilmette, Ill., assignor to Schwinn
Bicycle Company, Chicago, Ill.

Filed Mar. 13, 1970, Ser. No. 21,891

Term of patent 14 years

Int. Cl. D5—02; D12—14

U.S. Cl. D90—16

FIG. 1 is a plan view of a bicycle seat cover showing my new design before being applied to the seat and trimmed to fit; and

FIG. 2 is a perspective view thereof.

I claim:

The ornamental design for a bicycle seat cover, substantially as shown and described.
